(57) **CLAIM**

The ornamental design for a titrator, as shown and described.

DESCRIPTION

FIG. 1 is a front right perspective view of our new titrator design;

FIG. 2 is a front left perspective view of the titrator of FIG. 1;

FIG. 3 is a front view of the titrator of FIG. 1;

FIG. 4 is a right side view of the titrator of FIG. 1;

FIG. 5 is a left side view of the titrator of FIG. 1;

FIG. 6 is a rear view of the titrator of FIG. 1;

FIG. 7 is a top view of the titrator of FIG. 1; and,

FIG. 8 is a bottom view of the titrator of FIG. 1.

The features of the titrator shown in broken lines are for illustrative purposes only and form no part of the claimed design.
